LAMP SOCKET ADAPTER

Carl L. Goodlin, Wilkinsburg, and Thomas J. O'Meara, Pittsburgh, Pa., assignors to The Union Switch & Signal Company, Swissvale, Pa., a corporation of Pennsylvania

Application October 2, 1931, Serial No. 566,572
Renewed August 11, 1934

4 Claims. (Cl. 173—357)

Our invention relates to lamp-socket adapters, and particularly to adapters for accurately focussing incandescent-lamp filaments in precision devices, such as railway signals, although not limited to this field.

We will describe one form of adapter embodying our invention, and will then point out the novel features thereof in claims.

In the accompanying drawing, Fig. 1 is a side view, partially in elevation and partially in section, of an adapter embodying our invention, showing a lamp mounted therein and a support on which the adapter is mounted. Fig. 2 is a top plan view of the adapter. Fig. 3 is a side elevational view of the adapter, viewed in the direction of Fig. 1. Fig. 4 is a sectional view taken on the line IV—IV of Fig. 2.

Similar reference characters refer to similar parts in each of the several views.

Referring to Fig. 1, the device comprises in general, a support 2, the adapter 3 of our invention, and a lamp 4.

The support 2 comprises an insulating member of inverted substantially cup shape, and a socket member 6 secured thereto, as by rivets 7 extending through laterally-projecting portions 9 of the socket member 6 and through the insulating member. A terminal screw or binding post 10 is secured to the insulating member and connected to the socket member 6, as by a conducting strap 12 and the rivet 7. A spring connector 14 extends through an aperture 15 in the socket member 2 and is connected to a terminal screw 17. The terminal screws 10 and 17 are provided with heads 19 and nuts 20 at the under and upper sides, respectively, of the insulating member. The strap and spring connectors 12 and 14, respectively, may be mounted in grooves in the insulating member, as shown.

The socket member 6 is of the bayonet type having an accurately machined cylindrical body portion in which slots 22 of the usual substantially J-shape are disposed at opposite sides thereof.

Referring to Figs. 1, 2, 3 and 4, the adapter 3, of our invention, comprises a base portion 24 in the form of a metal cylinder having portions 25 and 26 of different exterior diameters, the lower portion 26 of smaller diameter being accurately machined to constitute a plug having relatively snug sliding fit with the socket member 6. The upper portion 25 is of greater diameter and wall thickness to provide suitable thread bases for two pairs of radially-extending screws 28 and 29 therein, the pair of screws 28 being at right angles

to the pair of screws 29 and in offset-plane relation thereto for a purpose hereinafter set forth. The upper portion 25 of the socket member 3 also has longitudinally-extending upper-edge slots 31 and relatively fine interior screw threads 32. The lower portion 26 of the socket member 3 carries diametrically-opposite bayonet-connector pins 34 for cooperation with the slots 22 in the socket member 6.

The adapter 3 further comprises a lamp socket 36 in the form of a tube telescopically related to the base portion 24 and rigidly carrying a ring-like element 38 having exterior screw threads for loose cooperation with the interior threads 32 of the base member 24. By this means, the remainder of the lamp socket being substantially radially spaced from the base member 24, the lamp socket 36 may be moved along and about the longitudinal axis of the base member 24 and still have sufficient play relative thereto to allow the axes of the lamp socket member 36 and the base member 24 to be tilted angularly about a pivot in the local zone represented by the ring-like element 38.

The screws 28 and 29 are distributed about the adapter in different places, in order that the screws 28 may bear against yieldable portions or ears 40 in the side walls of the lamp-socket member 36, and that the screws 29 may lie below the lower ends of the usual J-shaped bayonet slots 41 which are provided in the lamp-socket walls for cooperation with pins 42 on the lamp 4. Nuts 43 are provided on the screws 28 and 29 for locking the same in position.

In assembling the structure, assuming there are duplicate supports 2, one in service in a railway signal device and the other at the place of assembly, the adapter 3 is first placed in the support 2 at the place of assembly. Means, including a perforated screen and a telescope, not germane to this invention, are then employed to determine the position of the lamp filament relative to the socket member 6. By this means, the exact height, angular position, and position of tilt, if any, of the lamp-socket axis relative to the axis of the socket member 6 are determined.

The height is adjusted by turning the lamp-socket member 36 in the base portion 24. As soon as the necessary height adjustment has been made, the position of the pins 42 on lamp 4 relative to the pins 34 on the base portion 24 is adjusted to the proper position. This latter adjustment is made by sighting through the slots 31 in the upper edge of the base portion 24 and turning the socket member 36 away from the an-

gular position to which it was turned during the height adjustment, until the pins 42 are longitudinally opposite the slots 31, the slots 31 being in such angular positions relative to the pins 34 that, when the pins 42 are longitudinally opposite the slots 31, the pins 34 and 42 are properly related. It will be apparent that this angular adjustment will disturb the height adjustment a certain amount. It should be pointed out in this connection, however, that in order to make the proper angular adjustment, it is never necessary to turn the socket member more than a quarter of a revolution, and the threads on the base member 24 and on the ring element 33 are purposely provided with such a fine pitch that the resultant disturbance in the height adjustment will, from a practical standpoint, be insufficient to have any appreciable effect on the efficiency of any optical system with which the adapter is intended to be used, especially in view of the fact that the filaments of commercial lamps have a considerable length and therefore do not provide an exact point source of light. With the height and angular or turning adjustments thus effected, if the filament of the lamp is not laterally at the focal point desired, the screws 28 and 29 are adjusted until the exact focus is attained.

As indicated in Fig. 4, when the lamp 4 is placed in the socket member 36 it engages a plunger 45 at the lower end of the socket member. The plunger 45, which functions as an electrical connector between the center base contact on the lamp 4 and the spring 14 on the support 2, comprises a shank 46 that slidably extends through an insulating plug 47, a lower-end head 48 for engagement with the spring 14, an upper-end head for engagement with the center contact element of the lamp 4, and a spring 50 for holding the plunger in its upper position until engaged by the lamp. The spring and plunger structure also serves to hold the pins 42 more securely in position in the slots 31 of the lamp-socket member 36.

After the lamp 4 and the adapter 3 are adjusted at the place of assembly, as above described, they may then be taken to the duplicate support 2 at the point of service and mounted therein with absolute accuracy and without adjustment. When the lamp is renewed, the adjusting operation is repeated at the place of assembly because of discrepancies in the relation of parts of standard commercial lamps; it being one of the purposes of our invention to permit the use of ordinary lamps and render them absolutely accurate by this means.

One advantage of an adapter embodying our invention is that adjustments between the socket member 36 and base portion 24 necessary to locate the lamp filament at the desired height with respect to the socket member 6 of the support 2, and those necessary to obtain the proper position of the filament in the two vertical planes, may each be made separately in the manner previously described without materially disturbing the other adjustments.

Another advantage of an adapter embodying our invention is that since the adjusting screws 28 bear against the yieldable side wall portions 40 of the lamp socket member 36, when these screws are tightened, the side wall portions are pressed firmly into engagement with the base of

the lamp, thus securely locking the lamp in the socket member, and hence eliminating any possibility of the lamp changing its position in the socket member due to any clearance which might exist between the base of the lamp and the socket member. 5

While we have shown and described only one form of our invention, changes may be effected therein without departing from the spirit and scope thereof, as set forth in the appended 10 claims.

Having thus described our invention, what we claim is:

1. A lamp-socket adapter comprising a base constituting a plug at one end for cooperation 15 with a socket member, said plug and socket members being of the bayonet pin-and-slot type, a lamp-receiving socket member at the other end of the base, the lamp and the lamp-receiving socket member also being of the bayonet pin- 20 and-slot type, means for adjusting the lamp-receiving socket member relative to the base and sighting means providing for accurate relative positioning of the bayonet elements of the plug and socket elements of the adapter. 25

2. A lamp socket adapter comprising an internally screw threaded metal cylinder, the lower portion of which is accurately machined to provide a snug sliding fit with a lamp socket, a lamp socket member extending into the upper end of 30 said cylinder with considerable clearance, a ring element secured to said socket member within said cylinder and provided on its outer surface with screw threads which cooperate loosely with the threads on said cylinder, whereby the 35 socket member can be adjusted along and about the axis of said cylinder and can also be tilted a certain amount in any direction within said cylinder, and screws screwed through said cylinder and cooperating at their inner ends with said 40 socket member for tilting said socket member.

3. A lamp socket adapter comprising telescopically related sleeve and socket members, said socket member having yieldable side wall portions, and means cooperating between the members for adjustably moving the same in axial tilting relation including elements distributed about the members, certain of said elements extending through the sleeve against said yieldable side wall portions and cooperating therewith to force 50 said yieldable side wall portions into engagement with the base of a lamp which is mounted in said socket member to secure the lamp in a fixed position in said socket member. 45

4. A lamp socket adapter comprising telescopically related sleeve and socket members, said socket member having yieldable ears which are adapted to engage the base of a lamp which is mounted in said socket member to lock the lamp in a fixed position in the socket member, and means for adjustably moving said sleeve and socket members in axial tilting relation including two pairs of diametrically opposite screws screwed through said sleeve member in such manner that the inner ends of the one pair of screws engage said socket member at said ears and that the inner ends of the other pair of screws engage said socket member in offset plane relation to said one pair. 60 65
